UNITED STATES PATENT OFFICE.

ALEXANDER TISCHER, OF CHICAGO, ILLINOIS.

ADJUSTABLE SUPPORT.

1,155,383.

Specification of Letters Patent.

Patented Oct. 5, 1915.

Application filed June 25, 1913. Serial No. 775,629.

To all whom it may concern:

Be it known that I, ALEXANDER TISCHER, a citizen of the United States, residing at Chicago, in the county of Cook and State of Illinois, have invented certain new and useful Improvements in Adjustable Supports, of which the following is a specification.

My invention relates to adjustable supports and has for its primary object the provision of an improved support of this character which shall have improved means for supporting objects of different sizes.

With the above and other objects in view this invention consists substantially in the combination, arrangement, and construction of parts all as hereinafter described, shown in the accompanying drawings which form a part of this specification and show the preferred embodiment of my invention, and 20 more specifically set forth in the subjoined claims.

In the drawings: Figure 1 is a top plan view of a support constructed in accordance with the principles of my invention and 25 having portions of two of the legs thereof broken away. Fig. 2 is a bottom plan view of the device illustrated in Fig. 1 with portions of the legs thereof broken away. Fig. 3 is a section taken on the line 3—3 of Fig. 30 1 and looking in the direction indicated by the arrows.

Reference numeral 10 indicates a guide plate through the center of which passes a bolt 11. A spreading plate 12 is centrally pivoted upon the bolt 11 and secured by the bolt to the guide plate 10. The guide plate 10 is provided with a plurality of radial slots 13 and the spreading plate 12 is provided with a corresponding number of 40 curved slots 14 all curving outwardly in the same direction from a point adjacent the center of the bolt to a point preferably adjacent the periphery thereof. Each slot in the plate 10 is at all times in register at one 45 point with one of the slots in the plate 12, the points of register of the various opposite pairs of slots being equidistant from the center of the plates. A pair of lugs 15 formed upon the guide plate 10 carry a handled worm gear 16, and a portion of the periphery of the spreading plate 12 is provided with gear teeth 17 in mesh with the worm gear 16. By rotation of the worm gear 16 the spreading plate 12 may be os-

cillated with respect to the guide plate 10 to cause the registering points of opposite pairs of slots to approach or recede from the center of the plates. A plurality of legs 18, provided with downwardly extending feet 19 and strengthened in any suitable manner 60 by such means as the braces 20, are slidably positioned upon the plate 10 and secured thereto by means of cap screws or other suitable clamping devices 21 at their inner ends, the cap screws 21 serving, when 65 screwed down tightly, to bind together in fixed relation the plates 10 and 12, and the legs 18. Each of the legs 18 is provided at its inner end with an oblong guide block 22 which is disposed in the radial slot 13 70 and serves to guide the leg backward or forward in the slot and to prevent pivotal movement of the leg about the cap screw 21 as a center. At its inner end each of the legs 18 is provided with an upwardly extending toothed clamping jaw 23, the teeth of the clamping jaws projecting toward the center of the guide plate 10.

In the use of my invention an object to be supported, such, for instance, as a Christmas 80 tree, is positioned at the center of the guide plate 10. The cap screws 21 are then loosened to permit relative movement between the guide plates 10 and 12 and between them and the legs 18. By rotation of the worm 85 wheel 16 the legs are thereupon forced into close engagement with the object to be supported, the teeth being of assistance in binding the object within the support. Following this the cap screws 21 are tightened. 90

It is a feature of my invention that the device is readily taken apart and may be fitted into an extremely small packing space.

In the accompanying drawings and in the foregoing description is set forth the preferred embodiment of my invention, but it is obvious that one skilled in the art may make modifications thereof without departing from the spirit of the invention. 95

I claim:

1. The combination of a guide plate radially slotted, and adjusting plate pivoted at its center to the center of the guide plate and having radially curved slots crossing the slots of the guide plate, a plurality 105 of clamping jaws upon the outer face of the guide plate, elongated guide members formed upon the jaws, fitting the slots of the guide

plate and slidable therein, binding members passing through the slots of both plates and into the jaws, and means for oscillating the adjusting plate with respect to the guide 5 plate.

2. The combination of a guide plate radially slotted, an adjusting plate pivoted at its center to the center of the guide plate and having radially curved slots crossing 10 the slots of the guide plate, a plurality of clamping jaws upon the outer face of the guide plate, elongated guide members formed upon the jaws, fitting the slots of the guide plate and slidable therein, binding members 15 passing through the slots of both plates and into the jaws, and means for oscillating the adjusting plate with respect to the guide plate, comprising a worm wheel mounted upon one of the plates, and teeth formed 20 upon the other plate and in mesh with the worm wheel.

3. The combination of a guide plate radially slotted, an adjusting plate centrally pivoted to the center of the guide 25 plate and having radially curved slots crossing the slots of the guide plate, a plurality of clamping jaws upon the outer face of the guide plate, elongated guide members formed upon the jaws, fitting the slots of the guide 30 plate and slidable therein, cap screws passing through the slots of both plates and into the jaws, bearing lugs formed upon the guide plate, a handled worm wheel tangentially mounted for rotation in the lugs, and 35 teeth upon the periphery of the adjusting plate meshing with the worm wheel.

4. The combination of a horizontal plate, radially adjustable upright clamping jaws upon the plate, horizontal legs formed upon 40 the bottoms of the jaws and extending radi-

ally therefrom, and downwardly disposed feet upon the outer ends of the legs.

5. The combination of a horizontal plate, radially adjustable upright clamping jaws upon the plate, horizontal legs formed upon 45 the bottoms of the jaws and extending radially therefrom, and downwardly disposed feet upon the outer ends of the legs, said jaws being toothed on their adjacent sides.

6. The combination of an approximately 50 vertical toothed clamping jaw, an approximately horizontal leg formed upon the lower end of the jaw, and a downwardly disposed foot upon the outer end of the leg.

7. The combination of a plate, oppositely 55 disposed pairs of radially adjustable clamping jaws upon the plate, radiating legs formed upon the jaws, feet formed upon the legs, and means for simultaneous radial adjustment of the jaws, a part of said adjusting means serving to secure the jaws to the 60 plate.

8. The combination of a plate, oppositely 65 disposed pairs of radially adjustable clamping jaws upon the plate, radiating legs formed upon the jaws, feet formed upon the legs, and means for simultaneous radial adjustment of the jaws, a part of said adjusting means serving to secure the jaws to the 70 plate, said jaws being toothed upon their adjacent faces.

In testimony whereof I have signed my name to this specification, in the presence of two subscribing witnesses, on this 21st day of June A. D. 1913.

ALEXANDER TISCHER.
